[57] **CLAIM**

The ornamental design for a housing for vehicle interior gimballed light, as shown and described.

DESCRIPTION

FIG. 1 is a front elevational view of a housing for vehicle interior gimballed light showing my new design; FIG. 2 is a top plan view thereof, the bottom being a mirror image;

FIG. 3 is a rear elevational view thereof;

FIG. 4 is a left side elevational view thereof, the right side being a mirror image;

FIG. 5 is a sectional view taken along the line 5—5 of FIG. 1;

FIG. 6 is a front elevational view of a second embodiment of my new design;

FIG. 7 is a top plan view thereof, the bottom being a mirror image;

FIG. 8 is a rear elevational view thereof;

FIG. 9 is a left side elevational view thereof; and,

FIG. 10 is a right side elevational view thereof.

FIG. 5

FIG. 2

FIG. 1

FIG. 3

FIG. 4

FIG. 7

FIG. 6

FIG. 8

FIG. 9

FIG. 10
